UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,994, dated October 26, 1880.

Application filed July 31, 1880. Term of patent 3½ years.

To all whom it may concern:

Be it known that I, EDUARD LEISSNER, of New York, in the city and county of New York, have invented a new and original Design for 5 Wall-Paper, of which the following is a specification.

This invention relates to a new and original design for wall-paper and similar fabrics.

It consists in a novel grouping and configuration of figures hereinafter more fully described.

The accompanying photograph illustrates a face view of wall-paper having my new design.

15 The design consists in a vine bearing leaves, buds, and flowers of peculiar forms. It is shown in the photograph as applied to a border and as running between two parallel stripes.

20 A A A represent the main stalk of the vine, which runs in long semicircular curves, leaving spaces alternately above and below the stalk. From this stalk A branches off upward a flower-like figure, B, which occupies 25 one of the spaces above the stalk, and a similar figure, B', branches off downward below the stalk into the open space which comes next and which lies below the stalk A. Thus 30 the flowers B and B' alternate with each other, the flowers B occupying all the open spaces above the stalk A, and the flowers B' those below the stalk. These flowers B and B' consist of a thistle-shaped center surrounded by oval diverging leaves. From the stalk A, be-

tween the flowers B and B', branches off the 35 flower-like figure C, with a heart-shaped center, around which is a row of oval leaves, which are, in turn, surrounded by heart-shaped leaves. The buds a b d branch off from the stem A near this point and appear 40 around the flower C. A flower, D, branches off from the stalk A between the figures B' and B, the flowers C and D alternating upon the stalk. The flower D has a star-shaped center projecting from a leaf-like cup, and the 45 three buds e m g, growing on the stem A, appear around it.

I claim—

1. The design for wall-paper, consisting of the flower-like figure B, substantially as shown. 50
2. The design for wall-paper, consisting of the flower-like figure C, substantially as shown.
3. The design for wall-paper, consisting of the stalk A, with flowers B B' thereupon, substantially as shown. 55
4. The design for wall-paper, consisting of the stalk A, with flowers C thereupon, substantially as shown.
5. The design for wall-paper, consisting of the stalk A and flowers D thereon, substantially as shown. 60
6. The design for wall-paper, consisting of the stalk A and flowers B, B', C, and D, substantially as shown.

EDUARD LEISSNER.
